UNITED STATES PATENT OFFICE

ARTHUR E. PETERS, OF PHILLIPSBURG, NEW JERSEY, ASSIGNOR TO INGERSOLL-RAND COMPANY, OF JERSEY CITY, NEW JERSEY, A CORPORATION OF NEW JERSEY

COMPRESSOR

Application filed March 9, 1931. Serial No. 521,133.

This invention relates to compressors, but more particularly to compressors of the multi-stage type.

One object of the invention is to construct 5 a compact and efficient compressor apparatus of the multi-stage horizontal type requiring only a small amount of floor space and low head room.

Another object is to render the compressor 10 highly efficient and to simplify the construction of compressors of this type.

Other objects will be in part obvious and in part pointed out hereinafter.

In the drawings accompanying this specification and in which similar reference characters refer to similar parts,

Figure 1 is a side elevation of a compressor constructed in accordance with the practice of the invention,

20 Figure 2 is a plan view in section of the compressor taken through Figure 1 on the line 2—2 looking in the direction indicated by the arrows,

25 Figure 3 is a transverse view through the cylinders and the intercooler taken through Figure 1 on the line 3—3 looking in the direction indicated by the arrows, and

30 Figure 4 is a transverse view of the compressor cooling elements and taken through Figure 3 on the line 4—4 looking in the direction indicated by the arrows.

Referring more particularly to the drawings, A designates generally a compressor comprising a bed plate or main frame B in 35 the outer walls C of which are apertures C' and C² to accommodate anti-friction bearings D of a crank shaft E. One bearing D is seated directly in the aperture C' and the other bearing is seated in a bushing or sleeve 40 D' seated in the aperture C² and which aperture is of a suitable diameter to permit the crank shaft to be passed therethrough into the main frame. The main frame B is shown disposed upon a foundation F to 45 which it may be suitably secured by bolts G.

At one end of the main frame B is a cylinder casting H which may be secured to the main frame in any suitable and convenient manner. The cylinder casting H is provided with low and high pressure piston

chambers J and K arranged in parallelism and having disposed therein pistons L and O respectively.

The low pressure piston chamber J is closed at the free end of the cylinder casting 55 by a head P, and a closure is provided for the opposite end of the piston chamber J by a head Q having a bore R through which extends slidably a piston rod S carried by the piston L.

Similarly, the high pressure chamber K is sealed at the end adjacent the free end of the cylinder casting H by a head T and at the end adjacent the main frame B by a head U having an axial bore V to accommodate a 65 piston rod W carried by the piston O.

Although the piston chambers, and consequently the pistons, are of different diameters it is to be understood that the weights of the pistons L and O may be balanced in any convenient manner, as for instance, by constructing the piston L of material of lower specific gravity than the piston O or by otherwise suitably reducing the weight of the piston L to equal that of the piston O. The rods S 70 and W which, as may be observed, are substantially identical and therefore of the same weight so that the piston assemblies may be very accurately balanced.

Disposed within the interior or crank case 80 X of the main frame B are a pair of cross head guides Y to accommodate cross heads Z carried by the piston rods S—W. To the cross heads Z are connected, as by means of cross head pins b, connecting rods c which 85 are connected with their opposite ends to crank pins d carried by the crank shaft E. In order to effect a desirable balance of the movable parts of the compressing apparatus the crank pins d are oppositely disposed with 90 respect to each other and both crank pins d are located between the bearings D.

The compressor illustrated is of the double acting type in which air or other medium is compressed in each end of the piston chambers J and K. The compressor is accordingly provided at each end of both piston chambers with inlet and discharge valves designated by e and f respectively. The piston chamber J is shown as having two each of the dis- 100

charge and inlet valves at each end, and the piston chamber K may be provided with only one discharge and one inlet valve at each end thereof.

5 The medium intended to be compressed may enter the compressor through an inlet conduit *g* which opens into an inlet chamber *h* in the casting *H*. The admission of such medium into the opposite ends of the piston chamber *J* is controlled by the inlet valve or valves *e* associated therewith. Upon being compressed to a higher value the medium is discharged through the discharge valves *f* associated with the low pressure piston chamber 10 and into a discharge chamber *j* also in the casting *H*.

In one side of the discharge chamber *j* is an outlet opening *k* through which the compressed medium may flow into an intercooler 20 designated generally by *o*, thence from the intercooler through an outlet opening *p* into an inlet chamber *q* which, like the chambers *h* and *j*, may extend longitudinally of the casting *H* to afford communication between 25 the intercooler *o* and the inlet valves located at both ends of the piston chambers.

The flow of air from the inlet chamber *q* into the piston chamber *K* is controlled by the inlet valves *e* associated therewith. Upon 30 being compressed to a higher value such medium is discharged through the valves *f* into a discharge chamber *r* whence it may flow to the desired destination, as for instance, a storage receiver (not shown) through a discharge pipe *s*.

The intercooler *o* comprises a casing *t* arranged intermediate the ends of the casting *H* and is preferably an integral part of the casting *H* beneath which it is arranged to 40 support said casting. The casing *t* is provided with means such as pedestals or flanges *u* which rest upon a stepped portion *v* of the foundation *F* and to which it may be suitably secured by bolts *w*.

45 Disposed within the casing *t* are a plurality of cooling elements *x* which are superimposed with respect to each other and comprise a series of tubes *y* which extend longitudinally of the casing *t*. The tubes *y* of each 50 element are secured at their ends to heads *z*. In order to assure an intimate contact of the compressed medium with the tubes *y* during the course of the medium through the casing *t* the tubes *y* are provided on the exterior 55 surfaces with closely spaced fins 2.

The heads *z*, in effect, constitute water boxes for the tubes associated therewith. The heads *z* located at one end of the tubes, as for instance, at the left hand end as Figure 60 3 is viewed, may be connected directly and in any suitable manner to a cover plate 3 which forms a closure for that end of the casing *t*. The cover plate 3 may further serve as a part 65 of the circulatory system of the intercooler, as for instance, by forming therein a passage 4 to

conduct cooling water from one row of tubes *y* to another.

The cooling water employed for this purpose may be conveyed to the cooling element *x* by a conduit 5 which may lead from a suitable source of supply (not shown) and is connected to the cover plate 3. Preferably the conduit 5 is so arranged as to introduce the cooling water into the lowermost cooling element in the usual manner.

70 The heads *z* located at the opposite or right hand ends of the cooling elements are provided at their outer or free ends with a closure in the form of a cover 6 which may be suitably secured to the heads *z* and in this instance is provided with a passage 7 to afford 75 communication between the lowermost and intermediate cooling elements *x*.

The intermediate cooling element *x*, as will be observed, communicates with its opposite end with the passage 4 in the cover plate 3, so that the cooling water will follow a zigzag course through the elements, first flowing through the lowermost cooling element *x*, thence through the passage 7 into 80 and through the intermediate cooling element *x*, whence it flows through the passage 4 and through the uppermost cooling element *x* and from there is discharged through a discharge pipe 8 to the exterior of the intercooler 95 *t*.

In order that the compressed medium flowing through the intercooler *o* may be brought into repeated intimate contact with the tubes and, further, to extend the path of flow of 100 such medium through the said intercooler the casing *t* is provided therein with a series of baffles 9 and 10 which extend transversely of the casing *t*. The baffles 9 are seated on one side of the casing *t*, as for instance, against the upper surfaces thereof and, like the baffle 10, are of somewhat less width than the diameter or height of the casing, thus defining passages 11 around the ends of the baffles through which pressure fluid may flow 110 from one compartment to another of the intercooler. Owing to this manner of arrangement of the baffles the compressed medium will follow a serpentine course through the intercooler during its passage from the low 115 pressure piston chamber to the high pressure piston chamber.

120 As will be observed, the piston chambers *J* and *K* are provided with suitable jacketing spaces, as for instance, those designated by 12, 13 and 14 to conduct cooling water around the piston chambers for removing the heat due to compression from the compressing apparatus. The water utilized for this purpose may be introduced into the space 13 by 125 a supply pipe 15 and, after circulating through the water jacketing spaces, is again discharged from the compressor through pipes 15 and 16 which communicate with the spaces 14 and 12 respectively.

In practice, a compressor constructed in the manner described has been found to function in an unusually efficient manner. Among its desirable advantages are, that it is of compact construction and therefore occupies but a small area of floor space. By disposing the casing beneath the cylinder casting a convenient support is provided for the cylinders and their associated elements and at the same time the supporting means may be utilized as a container for the cooling elements to pre-cool the compressed medium prior to its admission to the high pressure piston chamber.

I claim:

- 15 1. In a multi-stage compressor, the combination of cylinders operating at different pressures, a casing through which pressure fluid flows from one cylinder to another, a cooling element in the casing to cool the compressed medium flowing therethrough and comprising cooling liquid conveying tubes, closely spaced fins on the tubes to conduct the compressed medium into intimate contact with the tubes, and baffles in the casing and being staggered with respect to each other to direct the compressed medium along a serpentine path through the casing.
- 20 2. In a multi-stage compressor, the combination of cylinders operating at different pressures, a casing through which pressure fluid flows from one cylinder to another, a plurality of separately disposed cooling elements in the casing to cool the compressed medium flowing from one cylinder to another and comprising cooling liquid conveying tubes and closely spaced fins on the tubes to conduct the compressed medium into intimate contact with the tubes, and baffles in the casing and being staggered with respect to each other to direct the compressed medium along a serpentine path through the casing.
- 25 3. In a multi-stage compressor, the combination of cylinders operating at different pressures, a casing through which pressure fluid flows from one cylinder to another, a plurality of separately disposed cooling elements extending throughout the length of the casing to cool the compressed medium and comprising cooling liquid conveying tubes and closely spaced fins on the tubes to conduct the compressed medium into intimate contact with the tubes, and baffles in the casing and being staggered with respect to each other to direct the compressed medium along a serpentine path through the casing.
- 30 4. In a multi-stage compressor, the combination of cylinders operating at different pressures, a casing integral with the cylinders conducting compressed medium from one cylinder to another and serving as a support for the cylinders, a plurality of separately disposed cooling elements extending longitudinally through the casing to cool the compressed

medium and comprising cooling liquid conveying tubes and closely spaced fins on the tubes to conduct the compressed medium into intimate contact with the tubes, and baffles in the casing and being staggered with respect to each other to direct the compressed medium along a serpentine path through the casing.

5. In a multi-stage compressor, the combination of cylinders operating at different pressures and being arranged in parallelism, a casing disposed beneath the cylinders to support the cylinders and to conduct compressed medium from one cylinder to another, cooling elements in the casing to cool the compressed medium, a main frame connected to the cylinders and having a crank case therein, pistons in the cylinders having piston rods, a pair of anti-friction bearings in the walls of the main frame, a crank shaft journalled in the bearings, cross heads in the crank case and being secured to the piston rods, and connecting rods connected at one end to the cross heads and with their opposite ends to the crank shaft at points between the

In testimony whereof I have signed this specification.
